DESIGN.

S. C. JACKSON.

RADIATOR CAP ORNAMENT FOR AUTOMOBILES.
APPLICATION FILED APR. 2, 1919.

55,615.

Patented July 6, 1920.

INVENTOR

Salome C. Jackson,
by her attorney,
J. Edward Shetland.

UNITED STATES PATENT OFFICE.

SALOME C. JACKSON, OF NEW YORK, N. Y.

DESIGN FOR A RADIATOR-CAP ORNAMENT FOR AUTOMOBILES.

55,615.

Specification for Design.

Patented July 6, 1920.

Application filed April 2, 1919. Serial No. 287,082. Term of patent 3½ years.

To all whom it may concern:

Be it known that I, SALOME C. JACKSON, a citizen of the United States, residing at New York, in the county of New York and State of New York, have invented a new, original, and ornamental Design for a Radiator-Cap Ornament for Automobiles, of which the following is a specification, reference being had to the accompanying drawing, forming part thereof.

The figure is a plan view of a radiator cap ornament for automobiles showing my new design.

I claim:

The ornamental design for a radiator cap ornament for automobiles as shown.

SALOME C. JACKSON.
